Des. 232,084
Patented July 16, 1974

232,084

MIRROR FRAME FOR TRUCKS OR THE LIKE

Kenneth J. Fischer, Jacksonville, Fla. (1/2 Road King
Industries, Inc., P.O. Box 548, Ashburn, Ga. 31714)

Filed Dec. 1, 1972, Ser. No. 311,133

Term of patent 14 years

The portion of the term of the patent subsequent to
Jan. 16, 1987, has been disclaimed

Int. Cl. D12—16
U.S. Cl. D12—187

FIG. 1

FIG. 2

FIG. 3

FIG. 4

FIG. 5

FIG. 6

FIG. 7

FIG. 8

FIG. 1 is a front perspective view of the mirror frame for trucks showing the first embodiment of my new design;

FIG. 2 is a top plan view of FIG. 1;

FIG. 3 is a rear elevational view of FIG. 1;

FIG. 4 is a cross-sectional view on an enlarged scale taken along line 4-4 of FIG. 2;

FIG. 5 is a front perspective view of the mirror frame for trucks showing the second embodiment of my new design;

FIG. 6 is a top plan view of FIG. 5;

FIG. 7 is a rear elevational view of FIG. 5; and

FIG. 8 is a cross-sectional view on an enlarged scale taken along line 8-8 of FIG. 6.

I claim:

The ornamental design for mirror frame for trucks or the like, substantially as shown and described.
